UNITED STATES PATENT OFFICE.

ALAN E. VOSBURG AND ROBERT B. WHITNEY, OF DETROIT, MICHIGAN, ASSIGNORS
TO ARTHUR V. HANNIFIN, OF CHICAGO, ILLINOIS.

BORING BAR AND THE LIKE.

Application filed February 6, 1922. Serial No. 534,623.

To all whom it may concern:

Be it known that we, ALAN E. VOSBURG and ROBERT B. WHITNEY, both citizens of the United States, residing at Detroit, in the county of Wayne and State of Michigan, have invented certain new and useful Improvements in Boring Bars and the like, of which the following is a specification.

This invention relates to certain improvements in boring bars and the like. The invention has reference particularly to improvements in the means for holding and locking the cutting tools within the boring bar, as well as the means for adjusting the tools to the desired gauge or cutting diameter.

More particularly the invention has to do with an improved construction of locking device whereby the tools are rigidly locked with respect to the boring bar after being set to the desired gauge. Still more particularly, the invention has to do with an improved locking device of very simple construction, and which can be very cheaply manufactured, but which may be very accurately made and which will be capable of exerting a very powerful locking action in order to securely hold the tools in position.

Still more particularly another object of the invention is to provide a boring bar and improved locking block therefor which may be interchangeably used with tools extending radially with respect to the boring bar, or tools slanting with respect to the axis of the boring bar and lying at an angle with respect to each other.

Still another object of the invention is to combine with such locking device and with the tools, an improved tool adjusting element for initially adjusting the gauge or cutting diameter of the tools with respect to each other and before they are locked solidly in the boring bar.

Other objects and uses of the invention will appear from a detailed description of the same, which consists in the features of construction and combinations of parts hereinafter described and claimed.

In the drawings:

Figure 1 shows a fragmentary face view of a boring bar having applied thereto a locking block embodying the features of the

present invention, the same being shown in association with a pair of angular cutting tools;

Fig. 2 shows a view corresponding to Fig. 1, with the exception that the central portion of the boring bar is shown in section and one corner of the locking block is cut away to more clearly illustrate the construction of the locking block itself;

Fig. 3 shows a cross section taken on the line 3—3 of Fig. 1, looking in the direction of the arrows;

Fig. 4 shows a cross section taken on the line 4—4 of Fig. 2, looking in the direction of the arrows;

Fig. 5 shows a view similar to that of Fig. 1, with the exception that the position of the locking block has been reversed and straight cutting tools have been substituted in place of the angular cutting tools illustrated in the earlier figures;

Fig. 6 shows a view at right angles to that of Fig. 5;

Fig. 7 shows a detail face view of the locking block, the set screws being removed;

Fig. 8 shows an edge view corresponding to Fig. 7; and

Fig. 9 shows a bottom face view of the adjusting scroll plate.

The boring bar itself is designated by the numeral 10 in the different figures. It is provided with a transverse slot 11, one edge 12 lying at right angles to the axis of rotation of the boring bar, and having its front end wall in the form of a pair of angular faces 13 and 14. The faces 13 and 14 lie at equal angles with respect to the axis of rotation, and in the construction illustrated, they slant outwardly away from the other wall 12 of the slot 11 so that the extreme outside portions of the slot are longer than its central portion.

Within the slot there are accommodated the cutting tools 15 and 16 and the locking block 17. The locking block has a straight face on one side together with a pair of angular faces 18 and 19 on its other side. The faces 18 and 19 are formed at equal angles with respect to the axis of rotation, and furthermore, said faces subtend between them the same angle as is subtended by the faces 13 and 14 of the slot 12. Consequently, the

faces 18 and 19 of the locking block 17 lie parallel to the faces 13 and 14 respectively of the slot when the locking block is set up solid against the end 12 of the slot 11.

- 5 The tools 15 and 16 have parallel edges and are set in between the locking block and the end of the slot 11. When the tools are set into the angular end of the slot 11, as shown in Figs. 1 and 2, the locking block 17
10 is seated squarely against the straight edge of the slot 11, whereas when the tools are set against the straight edge of the slot 11, as shown in Figs. 5 and 6, the locking block is set against the angular end of the slot 11.
15 The locking block may thus be used for locking either angular tools of the form shown in Figs. 1 and 2, or straight tools of the form shown in Figs. 5 and 6.

It is preferred that the inner ends of the tools be oppositely recessed, as shown at 20 in Figs. 1 and 2, so that the tools may be made longer and may have their inner ends overlapped as clearly illustrated in Fig. 3. A similar overlapping may be used when 25 straight tools of the form of Figs. 5 and 6 are substituted.

In order to adjust the amount of projection of the tools with respect to the boring bar any suitable adjusting device may be provided. The arrangement illustrated in the drawing is a very convenient and satisfactory one for this purpose. Said arrangement includes a circular scroll plate 21 set into a recess 22 in the face of the slot 11, as shown in Figs. 3 and 4. The bottom face of said scroll plate is provided with a spiral groove 23 which engages with teeth 24 and 25 on the inner portions of the two tools. Upon rotation of the scroll plate in the recess 22, the tools will be moved towards or from each other so as to correspondingly adjust the amount of projection. This rotation of the scroll plate may be effected in any convenient manner, as for example, by the 40 use of a hexagonal key inserted into a socket 26 in the face of the scroll plate. In such case a passage 27 is provided in the boring bar to give access to said socket 26.

The face of the scroll plate may be provided with a series of marks or graduations 28 which serve to indicate graduated amounts of movement of the tools by rotation of the scroll plate.

The arrangement illustrated is such that 55 the scroll plate turns within a recess 22 whose position is fixed with respect to the transverse slot 11 of the boring bar. Furthermore, the position of the scroll plate within said recess is such that its spiral groove will 60 properly mesh with the teeth 24 and 25 of the tools 15 and 16 when set into position against the angular walls 13 and 14, as shown in Figs. 1 and 2. By proper proportion of the parts, it is possible to secure 65 proper mesh of the teeth of the tools with

the groove of the scroll plate when the tools are set against the back straight face of the slot 11 in the position shown in Figs. 5 and 6.

The locking plate 17 is shown in detail in 70 Figs. 7 and 8, and is also very well illustrated in Fig. 2. It is provided with a pair of inwardly extending slots 29 and 30 which provide the wings 31 and 32 which are joined to the body of the locking plate by 75 means of the central tongue 33. The locking plate is also provided with inwardly extending threaded sockets for the accommodation of set screws 34 and 35, which may be threaded in or out with respect to the locking plate, being easily accessible from the outside of the boring bar, as will be readily appreciated from examination of Figs. 2 and 6 in particular. The threaded sockets of the locking plate, or the screws 34 and 80 35, or both, are tapered in such a manner that by rotating the screws a powerful wedging action is exerted which tends to spread the wings 31 and 32 of the locking plate, and thus bring about a powerful locking effect. In this way the tools are locked very securely in place. Furthermore, this wedging action will be secured no matter in which position the locking plate is set, whether that of Figs. 1 and 2 or that of 85 Figs. 5 and 6.

When the tools are being adjusted or changed, it is desirable to hold the locking plate in position within the slot, with at least sufficient force to prevent its unintentional removal. We have, therefore, provided a pair of relatively shallow sockets 36 and 37 in one face of the slot 11, and have also provided spring pressed balls 38 and 39 in the locking plate itself, which are adapted 90 to enter the sockets 36 and 37 under spring pressure. These balls are seated within the transverse passages 40 and 41 of the locking plate, the springs 42 and 43 pressing against the balls and being held in place by the stud screws 44 and 45 respectively. The opposite ends of the holes 40 and 41 are slightly reduced in size, so that the balls will not be fully projected when the locking plate is withdrawn from the slot 11. 115

While we have herein shown and described only certain embodiments of the features of our present invention, still we do not limit ourselves to the same except as we may do so in the claims. 120

We claim:

1. A boring bar comprising in combination a shaft having a transverse through slot, one end wall of which is straight and lies at right angles to the direction of rotation of the shaft and the other end wall of which is V-shaped with the two arms of the V intersecting on the axis of rotation and lying at equal angles with respect to the axis of rotation, a pair of cutting tools 125

locking plate, and means for expanding said slots to deflect the fins, substantially as described.

7. As a new article of manufacture a locking block comprising a plate having one of its end walls straight and its opposite end wall formed at an angle with respect thereto, there being a pair of inwardly extending

slots adjacent to one of the end walls establishing a pair of fins centrally joined to the body of the locking plate, and means for expanding said slots to deflect the fins for locking purposes, substantially as described. 10
